UNITED STATES PATENT OFFICE.

WILLIAM D. LUTZ, OF ALLENDALE, NEW JERSEY.

ELECTRICAL DOORLOCK.

Application filed January 29, 1921. Serial No. 440,868.

To all whom it may concern:

Be it known that I, WILLIAM D. LUTZ, a citizen of the United States, residing at Allendale, in the county of Bergen and 5 State of New Jersey, have invented a new and useful Electrical Doorlock, of which the following is a specification.

The present invention relates to electrical door locks, and more particularly to door locks for elevator systems. It comprehends, briefly, an improved form of lock which is applicable both to swinging and to sliding doors, without entailing substantial changes in the construction, and which, when employed with doors of the swinging type, may be made in duplicate as to certain of its component parts, so as to be capable of use in connection with double doors. When used with single doors of the swinging type, 10 it may be applied with equal facility to either right-hand or left-hand doors; that is to say, to doors whose closing movements take place either toward the right or toward the left.

According to the invention, there is preferably comprised in the improved lock a sliding bolt which is movable into and out of a lock case attached to the door frame and into which the electrical lead wires extend. During the closing of the door, the 15 bolt actuates a contact lever which is shifted thereby into a position in which it closes the electrical circuit, this contact lever being constructed in a special manner and carrying a specially constructed and mounted contact plate for coaction with the contacts in the lock case. Thereafter, the circuit remains closed until the bolt is subsequently withdrawn, at which time the movement of 20 the bolt pulls the contact lever and its plate in a direction away from the case contacts.

The invention, as described above, is capable of being installed in private residences, as well as in apartments, office buildings and the like; and in such instance it is preferably equipped with mechanism which acts to automatically prevent the door from being unlocked until the car arrives at a landing and while the circuit is closed.

An embodiment of the invention is illustrated in the accompanying drawings; but while such embodiment may be regarded for all present purposes as preferred, it is to be understood that no limitation to its precise

structural details is contemplated excepting 55 as may be imposed by the terms of the appended claims, as the invention is clearly susceptible of modifications and changes within the scope of the claims. Parts and features of the invention may also be utilized 60 separately without other parts, and in other and different environments.

In said drawings:

Figures 1 and 2 are, respectively, a front elevation and a part-sectional end elevation 65 of a single-door lock constructed in accordance with the invention, the cover of the lock case being omitted in Fig. 1 to disclose the interior mechanism;

Figure 3 is a front elevation of a double- 70 door lock;

Figure 4 is a vertical section on line 4—4, Fig. 3;

Figs. 5 and 6 are, respectively, a front elevation and a part-sectional plan view of 75 a slightly-modified construction which is designed for residence-type elevators; and

Fig. 7 is a vertical section on line 7—7, Fig. 5.

Referring more particularly to the drawings, 80 10 indicates in a general manner the bolt member of the lock, and 11 the lock case. The latter element is attached to the top of the door frame (not shown) in line with, or close to, the free vertical edge of 85 the door, and is provided with a removable cover plate 12. The bottom of the case has an opening 13 formed therethrough to admit the enlarged upper end or head 14 of the bolt 10, which is arranged vertically and is 90 slidably mounted in openings provided in a pair of spaced guides 15 formed on a base plate 16 which, in turn, is fastened to the door. The stem of the bolt is encircled by an expansible spring 17, which tends to 95 force it upward and which bears at opposite ends against the under side of the enlarged head 14 and the upper side of the lower guide 15, such movement being limited by a cross-pin 18 carried by the aforesaid head 100 14 for coaction with the upper guide. Withdrawal of the bolt against the action of spring 17 is effected by means of a chain, rod or analogous operating device (not shown) which is connected to the split lower 105 end 19 of its stem.

The bolt head 14 is designed to enter the case opening 13 at the completion of the

closing movement of the door, as will be understood; and during the course of this movement it is depressed on striking against the case, whether the door be of the swinging or of the sliding type. In the first instance, the opening 13 is extended through the back of the case and is beveled at its upper edge, as indicated at 20 (Figure 2), the front face of the bolt having a corresponding bevel 21; but in the second instance, the two bevels 20 and 21 may be omitted and one corner of the case may be provided with an inclined or beveled portion 22. For convenience in manufacture and installation, however, both bevels 20 and 22 are or may be provided on the case, so that the latter may be used with either type of door. The bevel 22 is formed on that end of the case which faces the door edge—that is, the end toward which the door moves in closing—the right-hand end in Fig. 1, which is assumed to represent a single left-hand lock.

The movement of the bolt into the lock case is utilized to operate a switch for closing the electric circuit, the two lead wires 23 of which enter the case through an opening in one end thereof, in which the pipe 24 which encloses said wires fits and is held in place by a screw 25. These two wires are connected at their terminals to binding posts 26 carried by a pair of metal contacts 27 and 28 which are fixed to a block of insulation 29 faced at opposite sides with micanite strips 30, the block and its two facing strips being suitably fastened to the top of the case. The aforesaid micanite strips project at opposite sides of the block of insulation, as shown in Fig. 2, and thereby provide channels or guides in which the two lead wires are disposed, this arrangement being particularly applicable to the double-lock construction illustrated in Figs. 3 and 4.

The circuit-closing or switch element which is actuated by the bolt, preferably consists of a lever 31 arranged within the case and comprising an angular arm or stem 32 and a flat body portion 33, the latter having a hook 34 at one end to engage in a notch 35 formed in the bolt head 14. Said lever is pivoted at the free upper end of its arm 32 on a pin 36, and its body portion supports a block of insulation 37 which is disposed beneath the contacts 27 and 28. The latter are disposed in spaced relation, and are adapted to be bridged by a contact plate 38 which is loosely mounted on a contact post 39 attached to the block 37. The post 39 is encircled by a coil spring 40 which yieldingly presses the plate upward, the upper portion 41 of said post projecting through a slot 42 in the plate and being reduced in size, so that the plate is capable both of rocking and of moving vertically on said post, its normal position being deter-

mined by means of a pair of cross-pins 43 carried by the reduced end 41 of the post against which it is pressed by the spring 40.

The construction illustrated in Figs. 3 and 4 is practically identical with that just described, excepting that the lock is intended for use with double doors and, hence, is of duplex character. The actual parts comprised in this form are the same as those in the first form, but two bolts are employed and, consequently, two switch levers or circuit closers and two sets of contacts. The reference numerals employed are the same as in the first form, the right-hand set of numerals having the prime mark applied to them. The lock case is designated 11', the cover 12', the two lead wires 23' and their pipe covering 24'. The two central contacts 23 and 28' are integrally connected, to pass the current from one set to the other, and the binding post 26' to which one of the wires is fastened is carried by the contact 27'.

The operation will be described with reference to Fig. 3, because in that figure one of the bolts is latched and the other unlatched, both positions thus being illustrated. In the normal position of the parts, and before either door is closed, the switch lever will swing by gravity into the position shown at the right-hand side of Fig. 3, which position, incidentally, it assumes automatically as soon as the bolt is withdrawn and immediately before the door is opened. Now when the door is shut, assuming that it is of the swinging type, the head 14 of the bolt will pass through the opening 13, and its beveled face 21 will strike against the beveled edge 20 of said opening, whereupon the bolt will be carried down in that obvious manner, and will immediately thereafter snap up into the case. On the other hand, if the door is of the sliding type, then the beveled face of the bolt will strike against the beveled surface 22 on the case and be forced down thereby, and will ride along the bottom of the case until it reaches the opening 13, whereupon it will snap up into said opening under the influence of its spring 17. In either instance, when the bolt head springs into the opening 13, its end will strike against the under side of the body portion 33 of the switch lever 31, and will cause said lever to swing upward, during which time the latching hook 34 on said lever will engage in the recess 35 in the bolt head and thus lock the bolt in projected position. As the lever swings upward, it carries with it the block 37 and connected parts, so that at the conclusion of the movement the contact plate 38 will engage and bridge the two contact terminals 27 and 28, the parts then occupying the position represented in Fig. 1 and at

the left-hand side of Fig. 3. Where a single door only is controlled by the lock, as in Fig. 1, this bridging of the two contact terminals will close the electric circuit. 5 But where double doors are involved, as in Fig. 3, then the other door will have to be closed and locked before the circuit is closed. The operation is precisely the same as that just described, the contact terminals 28' and 27' being engaged and bridged by the plate 38' at the conclusion of the movement of the door; and since the contacts 28 and 28' are integral, this bridging of the last-named contacts will have the 10 effect of closing the circuit.

With reference to the pairs of cross-pins 43 and 43' carried by the posts 39 and 39', it will be observed that one pin of each pair is located slightly higher than the 20 other. In consequence, when either switch lever is in its inactive or "down" position, its contact plate will assume a slightly inclined position relative to the upper face of the corresponding insulating block 37 or 25 37'. This is for the purpose of enabling the plate, just before it reaches the contacts 27 and 28 (or 28' and 27') to assume a position exactly parallel with the under faces of said contacts, so that it will strike 30 both of them simultaneously, the result being a double or two-point make and break of the circuit, which is of advantage.

The circuit-breaking operation is, of course, the reverse of the operation above 35 described; that is to say, the bolt is withdrawn by means of its associated operating element, and the switch lever or switch thereupon drops, thus breaking the circuit, the bolt head ultimately passing out of the 40 opening.

It will be observed that the bolt exerts a positive pull upon the switch lever during its descent, due to the interlocking engagement between the parts 34 and 35, which insures the downward movement of said lever and, hence, the breaking of the circuit, the parts becoming disengaged just before the top of the bolt head passes through opening 13. In the double-lock construction, the two 50 switch levers are reversely arranged, and the two recesses 35 and 35' in the bolt heads are formed in the outer edges thereof.

The construction illustrated in Figs. 5 to 7 is designed primarily for use in connection 55 with elevators installed in private residences, and is assumed to be applied to a single sliding door. The bolt 44 therein represented is pivoted horizontally at one end on a pin or stud 45 provided on a plate 46, and is formed with a central vertical loop 47 through which a second pin 48 on said plate projects. The opposite end of the bolt is formed with a nose or hook 49, and beneath said hook with a finger 50, the parts 49 and 60 50 being spaced apart by a recess 51. A

spring 52 is employed to normally hold the bolt in raised position, said spring being arranged within the loop and bearing at opposite ends against the top of the loop and the pin 48.

The hook end of the bolt is designed to enter and project through an opening 53 formed in the adjacent wall of the case 54, one edge of said opening being beveled as at 55 for coaction with the beveled edge 56 of the hook, so that during the entrance of the bolt it will first be depressed and will then snap up into locking position, as will be understood from Fig. 5. The bolt is utilized to shift a switch lever 57 into circuit-closing position, as in the forms previously described, such lever having a general angular shape and comprising two diverging arms 58 and 59, at the intersection of which it is pivoted on a pin 60 fixed in the case. 80 The arm 59 is adapted to enter the recess 51 when the bolt end moves into and through the opening 53, the result being that the switch lever is caused to swing in a clockwise direction. The outer portion of the arm 58 carries an insulating block 61 to which is fixed a post 62 carrying a spring-pressed contact plate 63, these parts being identical in construction, mounting and operation with the corresponding parts in the preceding 85 forms. Plate 63 serves to bridge a pair of spaced contact terminals 64 connected to an insulating block 65 which is faced on opposite sides with micanite strips 66, the two contacts 64 being equipped with binding posts to which the terminals of the line wires (not shown) are attached. The line wires enter the case through an opening in the top wall thereof, and will preferably be enclosed in a pipe or tube, as in the first form, their arrangement within the case being generally similar to that represented in Fig. 1.

Means are provided in connection with this form of the invention for preventing the unlocking of the door until the car reaches a landing. Accordingly, there is journaled in the lock case a horizontal rock shaft 67, to which is fixed a catch or dog 68. This dog or catch is arranged within the case immediately below the finger or projection 50 of the bolt, said finger having a notch or seat 69 formed in its under face. As shown in Fig. 7, the dog is stepped, its upper step or portion 70 having about half the width of its lower or body portion or step 71; and a spring 72 is associated with said dog to normally force it inward to a position directly beneath the bolt. If the dog is rocked part way only by the spring, its narrow upper step 70 will be brought in line with the seat 69, so that a slight downward movement of the bolt will still be permitted, such movement being sufficient to rock the switch lever leftward so as to break the circuit, but insufficient to disengage the hook 49 from the 120 125 130

adjacent wall of the case, so that the door remains locked. But if the dog moves all the way in, then the top of its said step 70 will be brought beneath and into immediate proximity to the unrecessed portion of the projection 50 and downward movement of the bolt will be completely prevented, the switch lever consequently maintaining its closed position. The dog is rocked backward (counter-clockwise in Fig. 7) against the tension of its spring by the action of a vertical arm 73, which is fixed to the rock shaft 67 and carries a roller 74 at its free end, the arrangement being such that when the car reaches a landing, the roller 74 will engage and be pushed backward by a cam (not shown) on the car, with the result that the said shaft 67 is rocked and, in turn, rotates the dog into ineffective position. When the cam passes beyond said roller as the car subsequently moves in one direction or the other the spring 72 will again exert its action and the dog will be swung into locking position.

25 The operation will be understood from the foregoing without further explanation, it being only necessary to state that the locking and circuit-closing operations occur simultaneously at the completion of the closing of the door, the latter remaining locked so long as the parts continue in circuit-closing position and until the car has reached a landing. The depression of the bolt, however, breaks the circuit, its hook 49 pressing down upon the arm 59 of the switch lever and thus forcing it to rock about its pivot 60 in a direction to separate the contact plate 63 from the contacts 64, the arrangement of the cross-pins carried by the post 62 enabling the plate to disengage both contacts 64 at the same time.

I claim as my invention:—

1. In a lock for electric elevators, the combination of a case having a bolt opening, a pair of spaced contacts in the case to which the line wires are connected, a switch in said case for bridging said contacts to close the line circuit, a bolt, and a part on which the bolt is mounted, said bolt, while the case and said part remain in a fixed relative position, being movable from a position outside of and free from the case, through said opening into position to operate said switch and to lock said part to the case.

2. In a lock for electric elevators, the combination of a case having a bolt opening, a pair of spaced contacts in the case to which the line wires are connected, a switch in said case for bridging said contacts to close the line circuit, a bolt, and a part on which the bolt is mounted, said bolt, while the case and said part remain in a fixed relative position, being movable from a position outside of and clear of the case,

through said opening into position to engage said switch and positively force it into contact-bridging position, the bolt when in said last mentioned position being operative to lock said part to the case. 70

3. In a lock for electric elevators, the combination of a case having a bolt opening, a pair of spaced contacts in the case to which the line wires are connected, a switch in said case for bridging said contacts to 75 close the line circuit, a switch arm carrying the switch, a bolt movable from a position outside of and free from the case, through said opening into position to engage said switch arm and move it to circuit closing position, said bolt having a recess adjacent its front end, and a hook on the switch arm moved into said recess by said movement of the switch arm and forming an interlocking connection between the 80 switch arm and bolt, operable to insure the line circuit being opened before the bolt is withdrawn.

4. In a lock for electric elevators, the combination of a case having a bolt opening, a pair of spaced contacts in the case to which the line wires are connected, a switch in said case for bridging said contacts to close the line circuit, a bolt movable from a position outside of and free from the 90 case, through said opening into position to engage and positively operate said switch, said bolt and switch having interlocking parts brought into interlocking engagement by said operation of the switch after the bolt has moved into the case and operable to prevent the withdrawal of the bolt from the case without the line circuit being opened. 100

5. In a lock for electric elevators, the combination of a case having a bolt opening; a pair of spaced contacts in the case to which the line wires are connected; a pivotally-mounted switch lever in said case; an insulated post carried thereby and provided with a pair of cross-pins, one of which is located nearer the free end of the post than the other; a contact plate for bridging said contacts loosely mounted on said post beneath said pins; a spring encircling said post and bearing against said plate to force the same against said pins, whereby said plate is maintained parallel with the surfaces of said contacts at the times of making and breaking contact therewith so as to engage and disengage said surfaces simultaneously; and a bolt movable through said opening into position to operate said lever. 110 115 120

6. In a lock for electric elevators, the combination of a case having a bolt opening; a pair of spaced contacts in the case to which the line wires are connected; a switch lever pivoted in said case for movement into contact-bridging position to close the line circuit; a bolt movable from a po- 125 130

sition outside of and free from the case, through said opening into position to operate said lever; and a member on said lever engaging said bolt, while the latter is projected into the case and forming a connection whereby the bolt, on being withdrawn, will pull said lever away from said contacts before the bolt has cleared the case.

7. In a lock for electric elevators, the combination of a case having a bolt opening; a pair of spaced contacts in the case to which the line wires are connected; a switch lever pivoted in said case for movement into contact-bridging position to close the line circuit; a bolt movable from a position outside of and free from the case, through said opening into position to operate said lever, said bolt having a recess in its front end; and a projection on said lever moved into said recess by the switch closing movement of the switch lever, whereby said bolt, on being withdrawn, will pull said lever away from said contacts before the bolt has cleared the case.

8. In a lock for electric elevators, the combination of a case having a bolt opening; an insulating block mounted in the case and faced on opposite sides with micanite strips, said strips projecting at opposite sides beyond said block to form receiving channels for the line wires; a pair of spaced contacts to which the line wires are connected disposed against one of said micanite strips and fastened to said block; a switch mounted in said case for bridging said contacts to close the line circuit; and a bolt

movable from a position outside of and free from the case, through said opening into position to operate said switch.

9. In a lock for double-door electric elevators, the combination of a case having a pair of bolt openings; two pairs of spaced contacts mounted in a row in said case, the two inner contacts being connected together to pass the current from one pair to the other, and the two outer contacts having the line wires attached to them; a pair of switches, one for bridging each pair of contacts, movably mounted in said case; and a pair of bolts movable through said openings to operate said switches, each bolt being attachable to one of the elevator doors.

10. In a lock for double-door electric elevators, the combination of a case having a pair of bolt openings; two pairs of spaced contacts mounted in a row in said case, the two inner contacts being connected together to pass the current from one pair to the other, and the two outer contacts having the line wires attached to them; a pair of switches, one for bridging each pair of contacts, movably mounted in said case; and a pair of bolts movable through said openings to operate said switches, each bolt being attachable to one of the elevator doors, and each switch automatically moving away from its associated pair of contacts when the corresponding bolt is withdrawn.

Signed at New York, in the county of New York, and State of New York, this 21 day of Jan., 1921.

WILLIAM D. LUTZ.
